PROCESS FOR THE ACTIVATION OF CLAY AND MANUFACTURE OF HYDROCHLORIC ACID

Filed June 1, 1931

UNITED STATES PATENT OFFICE

CHESTER TIETIG, OF LOS ANGELES, CALIFORNIA

PROCESS FOR THE ACTIVATION OF CLAY AND MANUFACTURE OF HYDROCHLORIC ACID

Application filed June 1, 1931. Serial No. 541,359.

This invention relates to a process by which clay may be activated so as to increase its adsorptive powers, and hydrochloric acid may be manufactured at the same time. It has among its objects the production of an activated clay having a specific high decolorizing power for oils and the production of two grades of hydrochloric acid, a pure grade and an impure grade. Gaseous H Cl may also be produced. By the practice of my invention, clay may be activated economically in many geographical locations, where otherwise the manufacturer would have to pay heavy freight rates if liquid acid were used. In my process, raw clay, hydrogen, chlorine water and steam are the only necessary raw materials.

Briefly stated, the invention comprises burning a jet of hydrogen in an atmosphere of chlorine, or vice versa, in the presence of clay particles carried in a gaseous or vapor stream. In this way, gaseous H Cl is generated, and this substance attacks the clay, particularly if steam has been injected into the flame.

The invention will be readily understood by reference to the accompanying drawing, which shows an apparatus also forming a part of the invention. While this apparatus is particularly well adapted to my process, it is to be understood that the process may be carried out in different apparatus.

In the drawing, which is a side elevational view, 10 represents a chamber in which the combustion takes place. Within the chamber are a plurality of baffles 11 and 12, the former arising from the floor 13 and the latter being suspended from the ceiling so as to produce a zigzag path for gases. The first baffle 12 is slanted toward the back of the chamber and is preferably made of refractory material. The preferred material for the entire chamber is acid-proof brick. The floor 13 is preferably slanted backward and in the extreme rear the slant is quite sharp so that a bin 14 results. In the bin, in a horizontal or other suitable position, is an auger screw 15 driven by electric motor 16, the screw serving to deliver activated clay

thru an opening 17 in the wall of the bin, and thence onto a chute 18.

Above the bin, near the roof of the chamber is a water spray or atomizing jet 19 fed from water pipe 20. In the rear wall of the chamber there extends a pipe 21 in which there is a valve 22 and to which is connected a steam ejector 23 or acid proof vacuum pump. The exhaust of the steam ejector pump is so arranged that vapor exhausting from it may be recovered, as indicated by the condensing chamber 24, the liquid outlet of which is shown at 25. This outlet is the source of the pure hydrochloric acid.

From the bottom of bin 14 a pipe 26 extends to a filter 27, thence to a pump 28, thence to a T outlet 29 in which there is a valve 30. A valve 31 is carried in the pipe 26 on the far side of the T. Ultimately, the pipe 26, the purpose of which is to carry impure, aqueous hydrochloric acid, joins a steampipe 32 and projects into the latter somewhat. The point of junction is after a steam valve 33 and before a raw clay feeding hopper 34. The outlet pipe 35 of the hopper is provided with an auger screw 36, driven by a motor 37, and the entire assembly, except the hopper, preferably set at a forward acute angle.

The steam pipe 32 joins the chamber 10 thru a burner 38, which may be of any construction suitable for the purpose. It may be so arranged that combustion takes place inside the burner 38, or inside the chamber 10, or the burner may be a mere mixing device, but in any case the burner has communication with the chamber. The burner may bear an ignition means (not shown), which may be a spark plug.

The hydrogen and chlorine are supplied to the burner from their respective cylinders or gasometers 39 and 40 thru tubing lines 41 and 42, respectively.

In operation the process functions in this apparatus as follows:

Finely ground activatable clay of the bentonite, smectite, fuller's earth or montmorillonite type is supplied to hopper 34. The fineness should be 200 mesh to the inch or over. Steam, preferably highly superheated, is then turned on in the ejector 23, and water

into atomizing jet 19. Chlorine is then supplied to the burner and chamber, from which air has been largely exhausted by the action of the steam ejector. Hydrogen is then supplied and the jet of this gas ignited so that the hydrogen burns in an atmosphere of chlorine. Steam valve 33 is then opened and steam supplied in limited quantity to the burner 38. Motor 37 is started and clay supplied to pipe 32 at a rate to be governed by the speed of the motor.

The clay activating action is due to the action of nascent H Cl on the clay and this action is assisted by the presence of steam. The steam also serves to lower the temperature of the H Cl forming flame, so that by regulating the rate of combustion and the steam supply, the heat will not be great enough to fuse or glaze the clay particles and so destroy their adsorptive quality. The ratio of hydrogen, chlorine and steam, as well as the flame intensity and clay supply are all to be regulated, so that the clay receives high or maximum activation. These adjustments will vary with the kinds of clay used, but a skilled chemical engineer will be able to make them.

The clay, together with the H Cl formed, will be carried over the baffles 11 and 12 to a large extent and in the travel be more thoroughly mixed with the hydrochloric acid. The bulk of the clay will be carried to the back of the chamber and will settle out in bin 14, where it will be washed with the stream of water from spray 19. A certain amount of H Cl will dissolve in this water giving an impure hydrochloric acid after the solution has remained in contact with the clay in the bin. This impure acid will percolate to pipe 26 by gravity.

H Cl vapors and chlorine, if any, will be drawn thru pipe 21 by the suction of the steam ejector. Passage of clay particles through this pipe will be prevented by a suitable filter over the outlet of the chamber. Since this vapor, as such will not carry impurities dissolved out of the clay, it will consequently be very pure when hydrated by the steam of the steam ejector and subsequently condensed.

When a suitable quantity of active clay has accumulated in bin 14, motor 16 is started and operated at such a speed as to remove the clay from the bin as fast as deposited. Clay which has not reached bin 14 may be removed from between baffles 12 by any suitable mechanical or manual means by doors in the chamber (not shown). Baffles 12 may be perforated near the bottom to allow condensed hydrochloric acid to flow to bin 14.

The impure acid solution which collects in bin 14 may either be returned to the burner 38 by injection into the steam supply therefor, or it may be taken out of the apparatus and sold commercially. It is first filtered thru

filter 27, then pumped by pump 28 either back to steam pipe 32 or else, by closing valve 31 and opening valve 30, ejected from the system. If fed back for re-use in activation, the projection of pipe 26 into pipe 32 materially assists in atomizing the acid. It is evident that in this apparatus and process only a comparatively small supply of new H Cl need be manufactured. The return thru the system is really a means of purifying some of the 75 impure acid.

The product from bin 14 is preferably given several water washes if it is to be used on animal or vegetable oils, but for mineral oils and waxes it may remain acid. For 80 organic oils it is preferably used dry; for mineral oils it may be used wet.

My process and apparatus is not limited to use in making new activated clay, but may be used in the same manner to revivify spent 85 clay or treat a mixture of raw and spent clay.

A return pipe and gas pump may be provided between the condenser 24 and the chamber 10 so that any chlorine or hydrogen drawn out of the chamber 10 thru the pipe 21 into the condenser 24 may be returned from thence to the chamber 10, where it may again take part in the H Cl forming reaction. Such a pipe and pumps will not usually be necessary however.

With certain kinds of clay it is not always necessary that steam should be injected into the flame, since some clays will stand high temperatures without glazing.

I am aware that a bleaching effect is 100 realized upon any material of generally similar characteristics to the clay which is put in place of the clay in my process. In consequence, it lies within the purview of my invention to so substitute finely divided barytes, kieselguhr, asbestos, fire clays and like materials to my process and to get a bleaching effect and iron removing effect, even if any activating effect be absent.

I claim as my invention:

1. The process of treating finely divided high-melting solid mineral material, which comprises injecting material into the flame produced by burning hydrogen and chlorine together.

2. The process of treating finely divided high-melting solid mineral material, which comprises injecting said material with the aid of steam into the flame produced by burning hydrogen and chlorine together.

3. A process, according to claim 2, in which the steam is highly superheated.

4. The process of activating clay and making hydrochloric acid, which comprises burning together hydrogen and chlorine in the 125 presence of a gaseous suspension of an activatable clay.

5. The process of activating clay and making hydrochloric acid simultaneously, which comprises burning a mixture of hydrogen 130

and chlorine together in the presence of aqueous vapor and of finely divided activatable clay.

6. The process of activating clay, which comprises burning together a mixture of hydrogen and chlorine in the presence in the flame of a suspension of a smectite clay in a current of steam, and then subjecting the residues of combustion to the presence of additional aqueous vapor, so that the clay is subjected to contact with liquid hydrochloric acid.

7. The process of simultaneously bleaching and/or activating finely divided high-melting mineral materials, which comprises injecting said materials into a flame produced by a burning mixture of hydrogen and chlorine, adding water to the reaction products while they are still gaseous and/or in gaseous suspension, allowing the clay particles to settle substantially and drawing off such acid vapors as remain uncondensed from a point above which the clay has settled.

8. A process according to claim 7 in which the clay is injected into the flame while in suspension in steam.

9. The process which comprises burning hydrogen in an atmosphere of chlorine, injecting into the flame a suspension of an activatable clay in steam, allowing the clay to subsequently settle out of the combustion products, hydrating a substantial proportion of the gaseous H Cl formed, allowing contact of the hydrated acid with the settled clay, removing the unhydrated H Cl and the hydrated H Cl separately and returning a substantial proportion of the hydrated H Cl to the current of steam in which the clay is to be suspended.

40 In testimony whereof, I have hereunto set my hand at Los Angeles, California, this 19th day of May, 1931.

CHESTER TIETIG.
